UNITED STATES PATENT OFFICE.

EDWARD KOEGER, OF CHICAGO, ILLINOIS.

JOINT FOR ARTIFICIAL LIMBS.

SPECIFICATION forming part of Letters Patent No. 727,383, dated May 5, 1903.

Application filed February 26, 1902. Serial No. 95,734. (No model.)

To all whom it may concern:

Be it known that I, EDWARD KOEGER, a citizen of the United States, residing at Chicago, in the county of Cook and State of Illinois, have invented certain new and useful Improvements in Joints for Artificial Limbs, of which the following is a specification.

My invention relates to improvements in joints for artificial limbs, and especially to ankle-joints.

The object of my invention is to provide a joint which shall be sufficiently flexible when in use to approximate the flexibility of a natural joint, and yet shall have sufficient rigidity to afford the desired degree of support.

Another object of my device is to provide such a joint, which may be adjusted so as to have more or less rigidity at the option of the user.

These and such other objects as may hereinafter appear are attained by the devices shown in the accompanying drawings, in which—

Figure 1 is a longitudinal sectional view through an artificial foot and ankle fitted with my improvements, and Fig. 2 is a vertical sectional view on the line 2 2 of Fig. 1 looking in the direction indicated by the arrows. Fig. 3 is a longitudinal sectional view through an artificial foot and ankle fitted with a modified form of my invention, and Fig. 4 is a vertical sectional view on the line 4 4 of Fig. 3 looking in the direction indicated by the arrows.

Like letters of reference indicate the same parts in the several figures of the drawings.

Referring by letter to the accompanying drawings, A indicates an artificial foot formed, preferably, of spongy rubber and covered by a flexible covering B. Embedded within the spongy-rubber body A is a core C, which is preferably formed of wood.

D is the ankle-piece, usually of a light wood, such as red willow, which is held or otherwise securely attached to a rocker E. The rocker E, as shown, is located above the core C, with a slight layer of spongy rubber between the opposing faces of the rocker E and core C. When in use, the weight of the body rests upon the rocker E, which has a slight rocking motion upon the core C.

Within the ankle-piece D is a supporting-

block F. Extending through the supporting-block F, rocker E, and core C is a bolt G, which at its lower end engages a soft-rubber washer H, which is seated within a recess in the under side of the core C. Screwed upon the upper end of the bolt G is a nut I, which engages a soft-rubber washer J, which rests upon the supporting-block F, the bolt G extending also through the washer J. The bolt G passes freely through the block F, rocker E, and core C, so as to have some degree of lateral play therein.

In the modified form of my invention shown in Fig. 3 the lower end of the bolt G is fitted with a cross-bar g, which has a rocking engagement with the under side of the core C. This construction has the double advantage of furnishing such rocking engagement and of avoiding all danger of the bolt being pulled upward through the core C. In this modified form I dispense with the compressible washer H, seated in the under side of the core C, and use a similar washer or sleeve H', surrounding the bolt G and seated within the rocker E. This compressible washer or sleeve not only lends desired flexibility to the joint, but prevents the clicking which might otherwise arise from the bolt G striking against the adjacent surfaces of the rocker E during the operation of the joint. Of course, if desired, the sleeve H' may be used in connection with the construction shown in Figs. 1 and 2, and, vice versa, the equivalent of the washer H 85 may be used in the structure shown in Figs. 3 and 4.

As shown in Fig. 2, the block F is supported within the ankle portion D by having a cone engagement with the inner surface of such ankle portion. As the block F therefore constitutes a wedge within the ankle portion D in the modified form illustrated in Figs. 3 and 4, I have shown this block as additionally supported within the ankle by means of dowel-pins f, which are used to overcome any possible danger of splitting the ankle portion when the nut I is tightened on the bolt G.

In the use of a foot fitted with my improvements as the body swings forward and the ankle-joint is flexed the rubber washers H J are compressed, and thereby give a yielding flexible movement at the ankle-joint, while

as the joint is relieved from the strain or weight of the body the expansion of the washers H J returns the parts to their normal position. If the joint is too flexible, the nut G 5 may be tightened any desired degree, thereby compressing the washers H J, thereby reducing the flexibility of the joint, whereas if the joint is not flexible enough it may be rendered more flexible by loosening the nut G.

10 Although I have shown in the drawings my preferred construction, it is evident that the advantages attendant on my invention will be attained to a considerable degree if either the washer H or the washer J be dispensed 15 with, the construction of the parts being otherwise substantially the same. I therefore do not confine myself to a structure embodying the use of both of said washers.

Having thus described my invention, what 20 I claim, and desire to secure by Letters Patent, is—

1. In an ankle-joint, the combination with a hollow leg-section and an elastic foot-section, of a supporting-block secured transversely within the leg-section, a core embedded within the foot-section, a bolt extending through said supporting-block and said core, and having a rocking bearing within said foot-section, a nut arranged to fit one end of 30 said bolt, and means arranged to be compressed by the tightening of said nut, substantially as described.

2. In an ankle-joint, the combination with a leg-section and an elastic foot-section, of a 35 core embedded in said foot-section, a connecting-bolt supported at one end within said leg-section and having a rocking bearing against said core, and a compressible washer seated within the lower end of said leg-section and surrounding said bolt, substantially as described.

3. In an ankle-joint, the combination with a leg-section and an elastic foot-section, of a 45 rocker upon the lower end of the leg-section and arranged to rest upon the foot-section, a core embedded within the foot-section, a connecting-bolt supported at one end within the

leg-section, and having a rocking bearing at its opposite end against said core, and a compressible washer interposed between said core 50 and said rocker, and surrounding said bolt, substantially as described.

4. In an ankle-joint, the combination with a leg-section and an elastic foot-section, of a rocker upon the lower end of the leg-section 55 and arranged to rest upon the foot-section, a core embedded in said foot-section, a connecting-bolt supported at one end within the leg-section, and having a rocking bearing at its opposite end against said core, and a compressible washer seated within said rocker, substantially as described.

5. In an artificial foot, the combination with a foot portion and an ankle portion, of a core embedded in the foot portion, a supporting-block in the ankle portion, a bolt engaging said core and extending freely therethrough and freely through said supporting-block, an adjusting-nut fitted to said bolt, and a compressible washer interposed between said nut 70 and said supporting-block, substantially as described.

6. In an ankle-joint, the combination with a hollow leg-section and a spongy-rubber foot-section, of a supporting-block arranged transversely within said leg-section, a core embedded within the spongy-rubber foot-section, a rocker at the lower end of the leg-section arranged to rest upon the foot-section, a connecting-bolt provided at one end with a cross-bar having a rocking bearing against said core, said bolt extending freely through said core, said rocker and said block, and being provided at its opposite end with a nut, a compressible washer, surrounding said bolt 85 and interposed between said nut and said block, and a second compressible washer seated within said rocker, projecting below the under side thereof and surrounding said bolt, substantially as described.

EDWARD KOEBER.
